CLAIM

The ornamental design for a warning light, as shown and described.

DESCRIPTION

FIG. 1 is a perspective view of a warning light showing my new design;

FIG. 2 is a top view thereof;

FIG. 3 is a first side view thereof;

FIG. 4 is a second side view thereof;

FIG. 5 is a front view thereof;

FIG. 6 is a rear view thereof; and,

FIG. 7 is a bottom view thereof.

The broken lines in the drawings represent unclaimed subject matter.
